UNITED STATES PATENT OFFICE.

FREDERICK WM. DUSTAN, OF CLARKSTON, WASHINGTON.

LOOSE-LEAF HOLDER.

1,114,596.

Specification of Letters Patent.

Patented Oct. 20, 1914.

Application filed April 2, 1913. Serial No. 758,445.

To all whom it may concern:

Be it known that I, FREDERICK W. DUSTAN, a citizen of the United States, residing at Clarkston, in the county of Asotin and State of Washington, have invented certain new and useful Improvements in Loose-Leaf Holders; and I do hereby declare the following to be a full, clear, and exact description of the invention, such as will enable others skilled in the art to which it appertains to make and use the same.

This invention relates to loose sheet holders or binders and an object of the invention is to provide a binder in book form which will be expandible for the purpose of accommodating a large number of loose sheets.

Another object of the invention is to provide a loose sheet holder with outwardly extending flaps for the purpose of separating the letters contained in adjacent leaves of the holder.

A further object of the invention is to provide a novel leaf construction for binders of this type wherein the leaves are made of a single blank folded, corresponding parts of the blanks being secured together in pairs to form the leaves.

A further object of the invention is to provide a leaf having a pocket formed on either side thereof for the reception of loose leaves.

A still further object of the invention is to provide a novel means for securing the ordinary tab to the leaves of the holder to form the index.

With these and other objects in view the invention comprises certain novel constructions, combinations, and arrangements of parts as will be hereinafter more fully described and claimed.

In the drawings: Figure 1 is a view showing a blank which is used in the making up of the holder herein described. Fig. 2 is an edge view of two sheets showing the separating outwardly extending flap in two positions. Fig. 3 is a plan view of the holder in open position. Fig. 4 is an edge view of one of the leaves showing loose sheets held on either side thereof. Fig. 5 is a corresponding view showing loose sheets being held in one side thereof. Fig. 6 is a section through part of the leaf showing a section through part of the leaf thereto. Fig. 7 is a section through one of the leaves of a modified form of the invention. Fig. 8 is a perspective view of the parts in Fig. 7 before they are assembled.

Referring to the drawings, and more particularly to Fig. 1, it will be seen that the blank has a line of scoring 1 which divides the same into two equal portions, this line of scoring together with adjacent scorings 2 serving to define the panels 3 of the back. Each half of the blank is provided with a scoring 4 which defines an end flap 5 adapted to be bent inwardly to hold the loose sheets. Just outside of the scoring 4 there are provided two additional lines of scoring 6 and 7, the utility of these scorings being shown more clearly in Fig. 2, where it is seen that they give the flap 5 an accordion hinge connection with the blank. In order to hold the member 5 in place there is provided a flexible strip 8 which preferably connects both ends of the pocket forming flaps 5 to prevent the slipping of loose sheets. As shown in Fig. 3, these strips 8 are adapted to secure adjacent ends of the flaps forming the pockets on each side of each leaf. Just inside of the lines of scoring 2 there is provided an additional scoring 9 for the purpose of rendering the back of the holder expandible for the reception of additional sheets. When it is desired to form a holder out of these sheets, the leaf portions 10 of the blanks included between the lines of scoring 2 and 4 are glued or secured in any other manner to corresponding portions of other blanks formed identical with the blank herein described, this construction being indicated in Fig. 2. This construction is also shown in Fig. 3, where all of the parts shown are formed of one blank, such as is shown in Fig. 1. The pocket forming flaps 5 are then bent so that one lies upon each side of the leaf 10 and the flexible strip 8 secured to the flaps as before described, to hold the ends 5 in place. In order to form the back the portion of the blank lying between the lines of scoring 9 is folded as indicated in Fig. 2 and the two parts secured to each other by gluing or any other means. When the holder is in folded position, the separating panels 3 will lie between adjacent leaves and will coöperate to hold the loose sheets in place.

- erate with the pockets formed on adjacent sides of adjacent leaves for the purpose of keeping the inner ends of the loose sheets held in the several pockets and will also 5 act as a separator. As more sheets are added the portion of the blank lying between the lines of scoring 2 and 9 will straighten out so as to increase the capacity of the holder.
- 10 By referring to Fig. 4 it will be noted that the strip 8 is not secured to the leaves 10, but only to the pockets and further that the holder is designed to carry an equal number of sheets upon each side of the leaf 10, and 15 in such case the strip 8 will just straddle the edge of the leaves 10. By referring to Fig. 5 it will be seen that it will be possible by reason of this construction to fill one side of the pocket completely and leave the other 20 side vacant, in which case the strips 8 will lie wholly upon one side of the leaf 10. In order that the strips 8 may be accommodated when the leaves do not contain sheets the blank is provided with cut away portions 11 25 extending from the line of scoring 4 inwardly as indicated in Fig. 1. By reason of the cut away portions the folded portions of the strips will not form bulky ends for the pockets.
- 30 As shown in Fig. 6, a tab 12 is secured between the blank sections forming the leaves 10, these tabs being secured by the same adhesive or other means used to hold the blank sections together. From the description of 35 this form of the invention it will be seen that the leaves are made up of blanks which are cut and folded in such a way as to form pockets on adjacent leaves and also to provide means for separating the sheets held by 40 the said pockets.
- The form of invention shown in Fig. 7 comprises a holder formed of leaves 13 which have extending therefrom and integral therewith tabs 14, these tabs as in the 45 case of the preferred form having printed thereon suitable letters for the purpose of forming an index. There is carried by the outer edge of each leaf an envelop or other structure suitable for forming a pocket 15, this pocket having a slit 16 formed therein through which the tab 14 passes. Secured upon the back of each of these envelops is a 50 strip 17 which is also secured to the tab 14. Insomuch as the strip 17 is not secured in any way to the leaf 13 except by means of 55 the tab 14 it will be readily seen that the same will allow papers or sheets to be held entirely within the envelop, and still form an effective means for holding said envelop 60 tightly to the leaves.

What I claim is:—

1. A loose sheet holder comprising a plurality of leaves, pocket forming members secured to the leaves, and tabs carried by

the leaves and projecting beyond the pocket 65 forming members.

2. A loose sheet holder comprising a plurality of leaves each having its upper and lower edges cut away at its outer end, and a pocket forming member carried by said 70 leaf with its ends passing through said cut-away portions to permit it to expand on either side of the leaf.

3. A loose sheet holder comprising a plurality of leaves, one-half of each of two 75 adjacent leaves being formed of one piece, and pockets formed integral with said piece, one on each of said leaves, for the reception of loose sheets.

4. A loose sheet binder comprising a plurality of leaves, one half of each of two 80 adjacent leaves being formed of the same strip of material, an indent portion of the strip lying between adjacent leaves, and pocket defining portions, one on each of said 85 leaves, integral with the said strip.

5. A leaf for loose sheet holders formed of a pair of strips of material secured together, each strip being provided with an indent portion, one of said indent portions 90 being located on each side of the leaf, and means for connecting adjacent ends of the portions to form a double pocket for the reception of loose sheets.

6. In a blank for leaves of loose sheet 95 binders, a strip of material provided with integral indent portions on each end thereof, and a central indent loop portion adapted to extend between the halves of the strip when the latter is folded.

7. In a leaf for loose sheet binders, a leaf 100 formed of a pair of strips of material each strip being provided with an indent portion, one of the indent portions lying on each side of the leaf and means for securing adjacent 105 ends of the indent portions to form pockets for the reception of loose sheets, each strip being provided with cutaway portions extending under the securing means.

8. A leaf for loose sheet holders made of 110 two plies secured face to face, each ply having its outer end turned inward to form a pocket, and means for connecting the respective ends of the pockets across the edges to the leaf.

9. A leaf for loose sheet holders made of 115 two plies secured face to face, each ply having its outer end turned inward to form a pocket, and strips secured to and connecting the respective ends of the pockets and 120 extending across the edges to the leaf without being attached to the latter.

10. A leaf for loose sheet holders made of 125 two plies, each ply having its outer end turned away from the other on accordion folds and carried inward in a pocket-forming flap, and pliable strips connecting the respective ends of said flaps and extending

across the plies without being attached to the latter.

11. A leaf for loose sheet holders made of two plies and having its upper and lower edges cut away at its outer end, each ply having its outer end turned away from the other on accordion folds and carried inward in a pocket-forming flap, and pliable strips connecting the respective ends of said flaps

and extending across the cut away portions ¹⁰ of the plies without being attached to the latter.

In testimony whereof I affix my signature in presence of two witnesses.

FREDERICK WM. DUSTAN.
